UNITED STATES PATENT OFFICE.

ELIAS P. HALL, OF CHICAGO, ILLINOIS.

DESIGN FOR A HANDLE FOR WINDOW-CLEANERS.

SPECIFICATION forming part of Design No. 12,583, dated November 29, 1881.

Application filed April 12, 1881. Term of patent 7 years.

To all whom it may concern:

Be it known that I, ELIAS PALMER HALL, a citizen of the United States, residing in the city of Chicago, county of Cook, and State of Illinois, have invented and produced a new and original Design for Handles for Window-Cleaners, of which the following is a specification, reference being had to the accompanying drawings, forming part thereof.

10 Figure 1 is a top view of my newly-designed handle, Fig. 2 is a side view thereof, and Fig. 3 is a cross-section of the same upon the line *x x*, these three views being deemed necessary to fully illustrate the design.

15 My design relates to metallic handles made in the form of a hollow cylinder having reticulated or open-work walls; and it consists in providing upon the upper side thereof an imperforate surface, substantially as hereinafter 20 stated.

A represents the grasp of the handle, which is a hollow cylinder with its sides perforated with openings *a*, of any tasteful shape and sufficiently prominent to give it the appearance of open 25 or reticulated work. Centrally upon the upper

side thereof is a solid or imperforate surface, *m*, substantially polygonal in form, with outlines harmonious in contour with the lines of the open-work whereof the cylinder is made, and with a raised ridge around the outside, so 30 as to give the surface a sunken appearance. This surface forms a convenient and appropriate place for the insertion of the manufacturer's name or other matter.

B is a plate or projection formed upon one 35 end of the grasp, and constituting the means of attachment to the cleaner. As clearly shown in Fig. 1, its exposed side and outlines are cut to imitate a leaf. The screw or screws whereby it is fastened may pass through this leaf 40 design without materially altering its appearance.

I claim—

The open-work handle provided with the solid surface *m* upon its upper side, substantially as set forth.

ELIAS PALMER HALL.
